UNITED STATES PATENT OFFICE.

HARRY D. FISTER, OF PHILADELPHIA, PENNSYLVANIA.

LIGHTING ATTACHMENT FOR CIGARS.

Application filed May 13, 1924. Serial No. 713,025.

This invention relates to new and useful improvements in attachments for cigars and has for its principal object to provide a simple and efficient means whereby the cigar 5 may be readily ignited by rubbing the attachment thereon over a surface.

A further object of the invention is to provide a lighting attachment of the above mentioned character, which will obviate the 10 necessity of the smoker having to carry about his person matches or any other independent lighting means for use in the lighting of a cigar.

A further object of the invention is to provide 15 a lighting attachment for cigars of the above mentioned character, which may be easily and readily placed upon the head of the cigar being adapted to form a part thereof when purchased so that the purchaser may 20 light the cigar without the use of matches.

A still further object of the invention is to provide an attachment of the above mentioned character, which is simple in construction, inexpensive, strong and durable 25 and furthermore adapted for the purposes for which it is designated.

Other objects and advantages of this invention will become apparent during the course of the following description.

30 In the accompanying drawing forming a part of this specification and in which like numerals designate like parts throughout the same:

Figure 1 is a side elevation of a cigar 35 showing my attachment associated therewith.

Figure 2 is a front end elevation of the attachment.

Figure 3 is a rear end elevation thereof, 40 and

Figure 4 is a sectional view taken through the attachment.

In the drawing wherein for the purpose of 45 illustration is shown the preferred embodiment of my invention, the numeral 1 designates generally my attachment and the same comprises a cap member 2 which is adapted to fit over the head of a cigar A and is frictionally supported thereon. The closed end 50 of the cap is provided with a series of spaced annular openings in the manner such as is shown at 3 in the drawing and these openings are preferably arranged adjacent the outer edge of the cap in the manner clearly

illustrated in Figures 2 and 3 of the drawings.

The closed end 4 of the cap has its central portion struck outwardly as illustrated at 5 and adapted to be supported on the outer face of the struck up portion is the 60 igniting head which may be preferably of phosphorous, and is illustrated at 6 in the drawing.

It is to be understood that the cap is formed of any suitable material which is 65 strong enough to endure the pressure exerted thereon when the cigar is lit and the cap member is further adapted to be impregnated with an inflammable substance so that when the phosphorus head 6 is ignited by 70 rubbing the same against any surface, the cap will immediately become ignited and the air hole 3 will assist in causing the cap to readily burn simultaneously lighting the head of the cigar so that the smoker may 75 light his cigar without the use of matches or the usual pocket lighters now on the market.

It will thus be seen from the foregoing description, that a lighting attachment for 80 cigars has been provided which is of such a construction as to enable the same to be readily placed on the head of the cigar and will form a part thereof so as to enable the purchaser of the cigar to be supplied with a 85 means for igniting or lighting the cigar without the aid of any independent lighting means such as matches or the like. The simplicity of my device enables the same to be manufactured at a very low cost and will be 90 further efficient and positive in carrying out the purposes for which it is designated.

While I have shown the preferred embodiment of my invention, it is to be understood that various changes in the size, shape and arrangement of parts may be resorted to without departing from the spirit of the invention and the scope of the appended claim.

Having thus described the invention, 95 what I claim is:—

A cigar lighter comprising an attachment for the outer end of the cigar, said attachment embodying an inflammable cap, and said cap including a disc of a diameter corresponding to the diameter of the coating 100 end of the cigar, the central portion of said disc being pressed outwardly to provide a cup-like projection spaced from the end of

the cigar, and the surrounding peripheral portion of the disc lying in direct contact with said end and being provided with an annular row of holes adapted to permit passage of air therethrough, diametrically opposed attaching wings carried by said disc, there being a single pair of such wings and these being shaped to conform to the contour of the body of the cigar, and a lighting tip of igniting substance carried by and disposed on the exterior of the aforesaid outwardly pressed cup like portion. In testimony whereof I affix my signature. HARRY D. FISTER.
